[57] CLAIM

The ornamental design for label printing and applying machine, as shown and described.

DESCRIPTION

FIG. 1 is a left side elevational view of a label printing and applying machine showing our new design, the right side elevational view being a mirror image thereof;

FIG. 2 is a top plan view thereof;

FIG. 3 is a front elevational view thereof;

FIG. 4 is a rear elevational view thereof;

FIG. 5 is a bottom plan view thereof;

FIG. 6 is a left front perspective view thereof.

FIG. 1

FIG. 2

FIG. 3

FIG. 4

FIG. 5
